MITER CLAMP

Will Krumbach, Highland Park, Ill., assignor to
Adjustable Clamp Company, Chicago, Ill., a cor-
poration of Illinois

Application August 19, 1937, Serial No. 159,918

3 Claims. (Cl. 144—293)

This invention relates, in general, to clamping devices. More particularly, my invention relates to a certain new and useful improvement in clamps especially, though not exclusively, adapted for the formation of miter-joints and has for its primary object the provision of a clamp which is uniquely constructed for convenient detachable engagement with the work-members, which may be easily manipulated for drawing the respective work-members tightly together with uniform pressure in buttwise-joint engagement and with the elimination of any defacing or marring of the visible faces or edges of the finished work, which readily enables accurate fitting and adjustment of the joint-parts during the clamping operation, and which is rugged, durable, and exceedingly economical in construction and efficient in use and operation.

And with the above and other objects in view, my invention resides in the novel features of form, construction, arrangement, and combination of parts presently described and pointed out in the claims.

In the accompanying drawing,

Figure 1 is a plan view of a clamp of miter-type constructed in accordance with and embodying my present invention;

Figure 2 is a vertical longitudinal sectional view of the clamp, taken approximately along the line 2—2, Figure 1; and

Figures 3, 4, and 5 are enlarged fragmental elevational views of slightly modified forms of work-gripping members forming part of the clamp of my invention.

Referring now in more detail and by reference characters to the drawing, which illustrates a preferred embodiment of the present invention, the clamp comprises a hand-screw in the form preferably of a suitably elongated cylindrical bar A equipped for a portion of its length with a right-hand thread 1 and for another portion of its length with a left-hand thread 2, such threaded portions 1, 2, being spaced by an intermediate non-threaded or plain portion 3, and suitably fixed on an end of bar A for convenience in manipulation of the clamp, is a suitable co-axial hand-grip 4.

B, B', designates blocks, which are respectively provided with oppositely threaded bores, as at 5, for accommodating engagement with, and for relative threaded adjustment by, the correspondingly oppositely threaded bar-portions 1, 2, the blocks B, B', being also formed with axially aligned transverse plain or smooth bores, as at 6, spaced laterally upwardly from, and extending

in parallel relation to, the bores 5, as best seen in Figure 2.

Fixed in, and extending lengthwise through, the plain bores 6, are respective tubular sleeves 7 each preferably having a length to extend equidistantly outwardly on opposite sides of its respective supporting-block, and each having an internal diametrical dimension for snugly slidably accommodating for free longitudinal movement a co-axially disposed cylindrical guide-rod C for retaining the blocks B, B', in upstanding parallel relation, the rod C being preferably upset or otherwise enlarged at its extremities, as at 8, for limiting its longitudinal movement and preventing its complete withdrawal from the sleeves 7.

Preferably integrally formed with, and extending outwardly in diametrically opposed relationship to the bores 5, 6, from the lower or base end b, of the blocks B, B', are respective work-engaging members or grippers 9, each preferably diametrically reduced or counter-bored for a portion of its length intermediate its ends, as at c, all for purposes presently more fully appearing and as best seen in Figure 2.

In use and operation, two work or wooden members D, D', are sawed or otherwise formed and shaped for miter joint formation in any conventional manner, the particular members D, D', here shown, being shaped with 45° end-cut portions for a right-angle miter joint, although it should be understood in this connection that the present clamp may be efficiently utilized in the formation of other similar types of joints. The members D, D', are suitably provided in their respective upper faces d with recesses or sockets 10, which are preferably disposed symmetrically and equidistantly on opposite sides of the juncture line j of the joint, and which extend downwardly into the respective members D, D', at right angles to their faces d to a depth preferably somewhat in excess of one-half the thickness of the wood.

The screw-bar A is then axially turned in one direction, whereupon the blocks B, B', are shifted away from each other a sufficient distance so as to permit the grippers 9 to be seated in the respective recesses or sockets 10. The screw-bar A is then axially turned in the opposite direction, whereupon the work-gripping blocks B, B', are drawn toward each other until the work-members D, D', are brought into loose abutting engagement along the juncture line j, when the members D, D', may be slidably moved or shifted with respect to each other for precise and exact joint-forming abutment, such shifting movement

being freely permitted through the pivoted engagement of the grippers 9 with the members D, D'.

Thus, during the initial adjustment, the member D is out of proper joint-forming alignment with the member D' and in the position shown in dotted lines in Figure 1 and the clamp will be disposed in the position also shown in dotted lines in Figure 1. However, through, as stated, the unique engagement of the blocks B, B', with the members D, D', the members D, D', may be relatively shifted with respect to each other and thereby brought into precise alignment, as shown in full lines in Figure 1, in which position the clamp will extend transversely across and normal to the juncture line j, also as shown in full lines in Figure 1. When the members D, D', have been so precisely aligned, the screw-bar A may be tightened down to first complete the clamping of the joint and then to rigidly retain the members D, D', in butt-wise engagement during the setting and hardening of any interposed adhesive.

Since, in the case of a joint formation between fairly thick members, there is some slight tendency for the joint to buckle, that is to say, to open up slightly along the finished face under clamping pressure, it has been found desirable to cut away or relieve the grippers 9, as shown at c, so that the clamp-pressure will be applied substantially at the center of the material of the work-members D, D', any buckling tendency of such members being thereby entirely overcome.

For certain types of work, it has been found desirable or preferable to provide a block B² having a work-engaging or gripping member 9' of frustro-conical contour, as shown in Figure 3.

For other types of work, it may be preferable to provide a block B³ having a work-engaging or gripping member 9'' of integral pin-like contour, which may be driven into the work. This particular type of work-gripping member is especially adapted for employment in the formation of miter joints in thin, lightweight structures, such as picture frames, or under other circumstances where the particular work-members to be joined do not permit the formation of recesses or sockets similar to the recesses 10; and it may be here stated that the blocks of the particular clamp may be provided with removable work-grippers, so that a wide variety of differently shaped work-grippers may be utilized according to the specific requirements of the particular joint being formed.

The clamp may also be of so-called universal type as particularly shown in Figure 5. In this form of the clamp, the blocks B⁴, while equipped with work-grippers 9, are somewhat thickened and provided to one lateral side of their respective bar and rod accommodating bores 5, 6, with diagonally extending bores e, as shown, for loosely or freely accommodating suitably sized nail-like grippers 9''', the blocks B⁴, in practice, being inverted, so that their normal flat top faces b² may be placed flatwise upon the particular work-members and the nails or grippers 9''' driven downwardly thereinto. And it may be stated in this connection that it has been found preferable to arrange the bores e, so that their respective axes lie in a single plane, and it has been stated that, by permitting the grippers 9''' to be driven diagonally into the work-members, the joint-forming force exerted by the clamp will be imposed upon the nail-like grippers 9''' substantially as shear stress, thereby practically elimi-

nating any bending forces which might otherwise distort the grippers 9''' and impair the strength of the joint.

Further, if desired, I may also provide a bridge-like member 11, which may be pinned or otherwise fixed or secured at its one extremity to the center portion of the guide-rod C' and provided at its outer extremity with a transversely extending bore 12 for rotatably accommodating the smooth intermediate portion 3 of the hand-screw A', all as best seen in Figure 5, the bridge-member 11 functioning not only in maintaining the guide-rod C' in permanently centered relationship with respect to the screw-bar A', but also in eliminating any "bowing" or binding of the guide-rod C' with respect to the screw-bar A' which may otherwise result when the clamp is used on large joints requiring excessive amounts of clamping pressure.

Thus, by my present invention, I provide a unique form of clamp, which is convenient in use and operation, is economical in construction, and which is so formed as to enable simple and efficient clampwise installation upon the work and precise and accurate adjustment of the work-members in joint-forming relation.

It should be understood that other changes and modifications in the form, construction, arrangement, and combination of the several parts of the clamp may be made and substituted for those herein shown and described without departing from the nature and principle of my invention.

Having thus described my invention, what I claim and desire to secure by Letters Patent is:

1. A clamp comprising, in combination, a pair of companion blocks each having a pair of parallel transverse bores, one of said bores being smooth, the other of said bores being threaded, and the threads of the latter bores being oppositely disposed, means including a rod lengthwise extending loosely through the set of smooth bores of the blocks for retaining the blocks shiftably in operative alignment, means on the block directly engageable in the work pieces being clamped for detachably securing the blocks to said work, and a bar having oppositely threaded portions engaging the threaded bores of the blocks for drawing the blocks together for securing the work-members in buttwise-joint-forming engagement.

2. A clamp comprising, in combination, a pair of companion blocks each having a pair of parallel transverse bores, one of said bores being smooth, the other of said bores being threaded, and the threads of the latter bores being oppositely disposed, means including a rod lengthwise extending loosely through the set of smooth bores of the blocks for retaining the blocks shiftably in operative alignment, means including projections on the blocks diametrically reduced intermediate their ends for insertion into the work-members for securing the blocks pivotally to the work-members and for bringing the clamping pressure to bear upon the work-members interiorly of their outer faces, and a bar having oppositely threaded portions engaging the threaded bores of the blocks for drawing the blocks together for securing the work-members in buttwise-joint-forming engagement.

3. A clamp comprising, in combination, a pair of companion blocks each having a pair of parallel transverse bores, one of said bores being smooth, the other of said bores being threaded, and the threads of the latter bores being oppositely disposed, means including a rod lengthwise

extending loosely through the set of smooth bores of the blocks for retaining the blocks shiftably in operative alignment, means including projections on the blocks of frustro-conical contour for insertion into the work-members for detachably securing the blocks pivotally to the work-mem-

bers, and a bar having oppositely threaded portions engaging the threaded bores of the blocks for drawing the blocks together for securing the work-members in buttwise-joint-forming engagement.
